(57) **CLAIM**

I claim the ornamental design for gaming desk, as shown and described.

DESCRIPTION

FIG. 1 is a front perspective view of a gaming desk, showing my new design;

FIG. 2 is a rear perspective view thereof;

FIG. 3 is a front perspective view thereof;

FIG. 4 is a bottom perspective view thereof;

FIG. 5 is a top perspective view thereof;

FIG. 6 is a rear perspective view thereof;

FIG. 7 is a left side view thereof; and,

FIG. 8 is a right side view thereof.

The broken line portion of the figure drawings is included to show portions of the article that forms no part of the claim design.
